CLAIM

The ornamental design for a compressor as shown and described.

DESCRIPTION

FIG. 1 is a perspective view of a compressor showing our new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof;

FIG. 8 is an enlarged view of the encircled area 8 of FIG. 1; FIG. 9 is an enlarged view of the encircled area 9 of FIG. 1; and,

FIG. 10 is an enlarged view of the encircled area 10 of FIG. 2.

The broken lines shown on the drawings depict portions of the compressor that form no part of the claimed design. In FIGS. 1, 2 and 8-10, the dashed broken lines of longer length encircling portions of the claimed design are illustrated in an enlargement view and form no part of the claimed design.
